UNITED STATES PATENT OFFICE.

JOHN F. BABBITT, OF LOUISVILLE, KENTUCKY, ASSIGNOR TO JOHN V. PILCHER, OF LOUISVILLE, KENTUCKY.

VANITY CASE.

Application filed December 2, 1926. Serial No. 152,193.

My present invention relates to improvements in vanity cases of the type containing a powder compact and mirror, and the invention aims to provide a device of this 5 character which will be of attractive appearance and capable of being economically produced, and which embodies a compact receptacle which can be used for powder in either loose or cake form. A further object 10 is to provide a vanity having a powder receptacle having as a cover a flexible perforated diaphragm which may be vibrated to expel the powder for use.

Another object is to provide improved 15 means for holding the receptacle in the case section, and for holding the diaphragm to the receptacle.

With these several objects in view the 20 invention includes the novel features of construction hereinafter described. What constitutes my invention being ascertained and defined by the appended claims.

An embodiment of the invention is illustrated in the accompanying drawing in 25 which:

Figure 1 is a central transverse section through the vanity case when in closed position.

Fig. 2 is a plan view with the cover section open. Fig. 2^a is a detail view.

Fig. 3 is a sectional detail on line 3—3 of Fig. 2.

Fig. 4 is an elevation of a modified form of case.

Fig. 5 is a view of the same open, similar to Fig. 2, and

Fig. 6 is a transverse section through the closed case.

In the following description for the convenience and to more clearly distinguish the parts I shall refer to the complete article as a "vanity".

This comprises a case of approximately watch case appearance comprising two sheet 45 metal sections designated 1 and 2 respectively, the former comprising the compact holder and the latter the mirror holder and being in effect the cover of the compact holding section. Each of these is provided with 50 a curved wall 1^a, and 2^a respectively which walls define substantially the depth of the case sections, though the bottom and top walls may be and are shown as slightly concavo-convex as a matter of attractive appearance, though they could be made flat if

desired as shown in Fig. 4 this being immaterial.

The curved edge of the body section 1 is provided with an upstanding flange 1^b designed to fit within the inturned edge of the 60 cover section when the case is closed to effect a tight closure.

Any suitable form of hinge may be provided for securing the sections together, but I prefer to use that shown comprising a 65 hinge eye 2^b integral with the cover section which fits in a cut away portion 1^c of the body wall and is engaged by a split ring 3 forming the hinge pintle which ring is sprung into engagement with the annular 70 internal channel formed by the peripheral curved wall of the body section 1. The mirror designated 4 is preferably retained in the cover section by a similar split ring 5. For holding the sections in closed position I 75 provide a very simple and economical form of catch which consists of a small nib or projection 6 on the flange 1^b opposite the hinge which projection may be formed by punching the flange outwardly intermediate 80 its height to form a rounded nib over which the edge of the cover section snaps.

7 designates the compact receptacle which is shaped to fit snugly in the section 1 and is adapted to hold powder in cake form 85 when desired. For retaining it in position I strike one edge outwardly to form a lip or teat 7^a which snaps under the edge of the wall of the body section. More than one of these could be provided if desired 90 but I have found one sufficient.

To enable the receptacle to be used for powder I provide it with a cover in the shape of a flexible diaphragm 8, preferably 95 of celluloid having a plurality of approximately centrally arranged powder exit openings 8^a.

The diaphragm being securely held at its edges, if it is vibrated, as by tapping, air 100 will be drawn in and expelled through the openings and will circulate beneath the diaphragm and when expelled will carry some of the powder with it for use. I have devised special means for holding the diaphragm which comprises a pair of interfitting rings of substantially L shape in cross section, designated 9 and 10 respectively, between the horizontal flanges of which the edge of the diaphragm is clamped.

The rings may be secured together with a 110

friction fit or be brazed or otherwise secured, and their vertical walls are of a height to hold the diaphragm flush with the upper edge of the receptacle. The outer 5 ring is made of a size to enter the receptacle and engage its annular wall with a friction fit which I find sufficient to hold it in place.

To enable the cover to be removed for 10 refilling I provide the outer ring with a small nib 9^a which when the receptacle is in place lies within the space formed by the punched out lip 7^a but is of less size so that a pointed instrument such as a knife 15 blade may be readily inserted to pry out the cover rings.

In some cases I may prefer to use a spring catch and such modification is shown in Figs. 4, 5 and 6.

20 In this form the compact receptacle 7' is made of smaller diameter and is provided with a peripheral flange 7^e at its upper edge for fitting snugly within the upper edge of the compact.

25 A catch 11 similar to that disclosed at 5 in my Letters Patent #1,596,790 is secured to a free end of the split ring 3 which cooperates with the edge of the cover section, the flange 7^e having a cut-away portion 7^d to 30 allow inward movement of the catch.

Having thus described my invention what I claim is:

1. In a vanity a pair of circular case sections hinged together and having inwardly 35 curved walls abutting when the case is closed, and a powder receptacle in one of said sections having an integral lip or pro-

jection for snapping into engagement with the inturned edge of the wall of said section, ring means frictionally held within the wall of the receptacle, and a resilient diaphragm having openings in the central part only and a peripheral edge rigidly supported by said ring means.

2. In a vanity a pair of case sections 45 hinged together and having curved walls abutting when the case is closed, and a compact receptacle in one of said sections having an integral lip or projection for snapping into engagement with the edge of the 50 wall of said section, ring means frictionally held within the wall of the receptacle, and a flexible diaphragm having central openings and a peripheral edge rigidly supported by said ring means, said ring having 55 a nib or projection lying in the space formed by the lip on the receptacle and of less size than said space.

3. In a vanity case, a pair of circular case sections, one of which forms a powder container and the other a cover therefor, said powder container having an inwardly curved wall, the edge of which abuts the edge of the cover section when closed, a powder receptacle in said powder containing section with means for holding it detachably therein, a pair of rings held within the wall of the receptacle, and a resilient diaphragm having openings in the central part only and having a peripheral edge clamped between said rings.

In testimony whereof I affix my signature.

JOHN F. BABBITT.
